(57) **CLAIM**

The ornamental design for a display screen with transitional graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a user interface for a display screen showing a first image in a sequence of transitioning images;

FIG. 2 is the user interface for a display screen of FIG. 1 showing a second image in the sequence of transitioning images, according to a first embodiment; and

FIG. 3 is a user interface for a display screen showing a first image in a sequence of transitioning images.

FIG. 4 is the user interface for a display screen of FIG. 3 showing a second image in the sequence of transitioning images, according to a second embodiment.

FIG. 5 is another view of FIG. 1 but shown without the broken lines illustrating portions of the graphical user interface, for clarity of illustrating the claimed design;

FIG. 6 is another view of FIG. 2 but shown without the broken lines illustrating portions of the graphical user interface, for clarity of illustrating the claimed design;

FIG. 7 is another view of FIG. 3 but shown without the broken lines illustrating portions of the graphical user interface, for clarity of illustrating the claimed design; and,

FIG. 8 is another view of FIG. 4 but shown without the broken lines illustrating portions of the graphical user interface, for clarity of illustrating the claimed design.

The outermost broken line in each figure illustrates a display screen. The remaining broken lines in the figures illustrate

See Figure(s) in Checklist				
	Significance	Location #1	Action Item needed?	Notes
Chemical Feed System Appearance	Functionally related to safety equipment designed to operate safely and reliably.	☐	☒ (Selected)	+
Overall Appearance	Entire device or related device feed system.	☐	☐ (Select)	+
Task Coordination	Safety equipment to certain chemical feed.	☐	☐ (Select)	+
Task Labeling	SDI and hazard communication labels of process batch feed tanks and controls.	☐	☒ (Selected)	+

See Figure(s) in Checklist				
	Significance	Location #1	Action Item needed?	Notes
Chemical Feed System Appearance	Functionally related to safety equipment designed to operate safely and reliably.	☐	☐ (Select)	+
Overall Appearance	Entire device or related device feed system.	☐	☐ (Select)	+
Task Coordination	Safety equipment to certain chemical feed.	☐	☐ (Select)	+
Task Labeling	SDI and hazard communication labels of process batch feed tanks and controls.	☐	☒ (Selected)	+

portions of the graphical user interface. None of the broken lines form part of the claimed design.

The appearance of the user interface sequentially transitions between the images shown in FIGS. 1 and 2, FIGS. 3 and 4. The process or period in which one image transitions to another image forms no part of the claimed design.

**1 Claim, 8 Drawing Sheets
(4 of 8 Drawing Sheet(s) Filed in Color)**
